UNITED STATES PATENT OFFICE.

LOUIS N. VINCENT, OF PRESCOTT, ARIZONA.

DRAIN-VALVE.

1,227,098.

Specification of Letters Patent. Patented May 22, 1917.

Application filed October 3, 1916. Serial No. 123,517.

To all whom it may concern:

Be it known that I, LOUIS N. VINCENT, residing at Prescott, in the county of Yavapai and State of Arizona, a citizen of the United States, have invented certain new and useful Improvements in Drain-Valves; and I do hereby declare the following to be a full, clear, and exact description of the invention, such as will enable others skilled in the art to which it pertains to make and use the same.

My invention relates to improvements in automatic drain valves.

It has for its object to provide an automatically operated drain valve for use in connection with the steam cylinders of locomotives and other engines, steam pipes and the like which remains normally open when the steam pressure thereon is released, to allow the water of condensation to be drained therethrough, and closes by steam pressure introduced through the steam inlet.

It further has for its object to provide a drain valve which is automatically closed by steam pressure and automatically opened when the steam pressure is released.

It further has for its object to provide a drain valve having a minimum number of parts and to mount the working elements thereof in one part so that when said part is removed the working elements will also be removed.

It further has for its object to provide means whereby any and all foreign matter which may collect in the drain valve and clog it up and hinder its operation may be quickly eliminated without dismembering the several parts of the same.

It further has for its object to provide a drain valve which is simple, inexpensive and durable in construction and easy and effective in operation.

The invention consists in the several features and in the construction, combination and arrangement of such features as more fully hereinafter described and claimed.

Referring to the drawings:

Figure 1 is an elevation of the drain valve. Fig. 2 is a central vertical section of the drain valve showing the position the several parts assume when under steam pressure and both drain ports closed in full lines, and showing the position the several parts assume when released from steam pressure and both drain ports open in dotted lines.

Fig. 3 is a top plan view.

Fig. 4 is a cross-section on the line $\alpha-\alpha$ of Fig. 2.

Fig. 5 is a side elevation of the valve and valve stem.

Fig. 6 is a top plan view of the valve.

Fig. 7 is a bottom plan view of the valve.

In the drawings in which similar reference characters denote similar parts throughout the several views, 1 represents the drain valve having an outer member or casing 2 and an inner member or plug 3. The outer member or casing 2 is provided at the top with a hollow screwthreaded extension 4 adapted to be connected with a high pressure inlet pipe 5 communicating with the steam chest of a steam cylinder, when the valve is employed in connection with a steam cylinder, and just below the screwthreaded extension a hexagonal portion 6 is provided adapted for the application of a wrench or other tool.

The interior of the outer member or casing 2 is provided with a shallow annular chamber 7 just below and communicating with the hollow screwthreaded extension 4 which in turn communicates with the high pressure inlet pipe 5, and below the chamber 7 a larger chamber 8 is provided.

High pressure by-pass ports 9, preferably facing each other, connect the chamber 7 with the chamber 8 and each by-pass port comprises a lateral horizontal channel 10 and a vertical communicating channel 11 having a downwardly and inwardly curved lower end 12, for the purpose of assisting in the passage of the water of condensation therefrom, and 13 are screwthreads which are formed on the interior of the outer member or casing and extend from the chamber 8 to the lower edge of the outer member or casing.

The inner member or plug 3 is provided on its exterior with an upper screwthreaded portion 14 adapted to be secured in the outer member or casing 2 and to engage the screwthreads 13 thereof, a flange 15 to abut against the lower end of the outer member or casing 2, a hexagonal portion 16 adapted for the application of a wrench or other suitable tool when it is desired to grasp the same to insert it or remove it from the outer member or casing, and a hollow screwthreaded portion 17 adapted for connection with an exhaust pipe not shown.

The interior of the plug is provided with a chamber 18 which communicates with the

hollow portion 17, and the chamber being larger in circumference than the opening in the hollow portion 17 a shoulder 19 is formed at the point where they meet and the inner upper edge of the chamber is beveled as at 20 to facilitate the flow of water or condensed steam into the same.

A valve 21 is operatively contained within the outer member or casing 2 and bodily mounted in the inner member or plug 3 and comprises a circular disk 22, which is a little less in width than the length of the by-pass high pressure ports 9, seated and adapted to reciprocate in the chamber 8 and having an upwardly extending projection 23 seated in the chamber 7 and provided with a cross slot 24, a stem 25 depending from the lower face of the disk 22, mounted in the hollow portion 17, and provided with a plurality of longitudinal exhaust channels or grooves 26 extending from end to end thereof and having sharp cutting edges 27.

The purpose of the sharp cutting edges 27 is to remove any foreign matter which may accumulate in the plug and retard its operation by applying a screwdriver to the slot 24 in the projection 23 and then turning the valve and stem, and in order to accomplish this it is only necessary to remove the high pressure pipe to get access to the slot 24 and it does not require the dismemberment or taking apart of the several parts of the drain valve.

A spiral spring 28 is mounted on the stem 25 between the disk 22 and the shoulder 19 and serves to normally retain the disk against the top of the chamber 7 and thus hold the valve in its open position until steam pressure from the high pressure inlet forces the disk downward and closes the valve and ports.

By reason of the several by-pass ports being formed directly in the members, by boring, pipes are entirely dispensed with, and by reason of the plug member bodily carrying the valve, valve stem and spring they can be removed and also inserted without being taken out of the plug member or being displaced.

In operation, steam under pressure passes through the high pressure inlet pipe and hollow extension 4 into the chamber 7 and forces the valve 21 down upon its lower seat, formed by the upper edge of the plug member 3, compresses the spiral spring 28 and closes the by-pass high pressure ports 9 and when the valve is released from the steam pressure the spring 28 expands and forces the valve against its upper seat in the top of the chamber 8, whereupon all

the condensed steam or water passes through the chamber 7, by-pass high pressure ports 9 and also the chamber 18 and thence through the longitudinal channels 65 in the stem of the valve and the hollow portion 17 of the inner member or plug to the exhaust pipe.

I do not wish to be understood as limiting myself to the specific details of construction and arrangement as herein described and illustrated, as it is manifest that variations and modifications may be made in the features of construction and arrangement in the adaptation of the device to the various conditions of use without departing from the spirit and scope of my invention and improvements.

I therefore reserve the right to all such variations and modifications as properly fall within the scope of my invention and the terms of the following claims.

What I claim is:—

1. A drain valve comprising a member provided with a chamber and an inlet thereto, by-pass ports of substantially uniform cross-section in said chamber, a second member provided with an outlet and having a free end terminating at substantially one end of the by-pass ports and providing a valve seat, a valve member having an imperforate disk head coöperating with said seat, and a solid guiding stem in said outlet, and means for retaining said valve in a normally open position. 95

2. In a drain valve, an outer member, an inner member, a valve mounted in the inner member and provided with a plurality of substantially straight grooves and straight cutting edges between said grooves, 100 said valve adapted to be positively rotated to remove any foreign matter which may accumulate in the inner member.

3. A drain valve comprising a member provided with a chamber and an inlet thereto, by-pass ports of substantially uniform cross-section in said chamber, a second member provided with an outlet and having a free upper end terminating at substantially the lower end of the by-pass 110 ports and providing a valve seat substantially in alignment with the end of said ports, a valve member having an imperforate disk head coöperating with said seat, and an elongated solid guiding stem in said outlet provided with longitudinally extending external grooves and means for retaining said valve in a normally open position contained within said inner member. 115

In testimony whereof I have affixed my signature.

LOUIS N. VINCENT.
